UNITED STATES PATENT OFFICE.

AMBROSE SWASEY, OF CLEVELAND, OHIO, ASSIGNOR TO THE WARNER
AND SWASEY COMPANY, OF SAME PLACE.

LATHE-CHUCK.

SPECIFICATION forming part of Letters Patent No. 670,213, dated March 19, 1901.

Application filed January 7, 1901. Serial No. 42,277. (No model.)

To all whom it may concern:-

Be it known that I, AMBROSE SWASEY, a citizen of the United States, residing at Cleveland, in the county of Cuyahoga and State of Ohio, have invented a certain new and useful Improvement in Lathe-Chucks, of which the following is a full, clear, and exact description, reference being had to the accompanying drawings.

10 The invention is an improvement in the kind of chucks which are employed in screw-machines, turret-lathes, and analogous machines to grasp and hold the work-rods—that is to say, the rods on which the machine is 15 to operate. The object of the invention is to render such chucks easily and quickly adaptable for holding work-rods of different sizes and shapes.

Heretofore some lathe-chucks have included a conical tubular core which is split longitudinally, so as to be compressible, a shell in which said core is movable, and bushing-sections removably secured in the core to vary its internal size and shape to 25 adapt it to grasp different rods. In all such prior chucks, however, the means for holding bushing-sections in the core could not be operated from the front of the core and shell, and consequently the bushing-sections 30 could not be changed without considerable difficulty.

The generic difference between the chuck embodying my invention and the prior chucks is that the bushing-sections are fastened to the jaws of the core by catches whose operating mechanisms project out 35 from the exposed forward end of said core, whereby said catches may be operated without separating the core and shell.

40 The invention consists, broadly, in the combination of the core having a plurality of compressible jaws and a surrounding shell with bushing-sections, catches adapted to removably secure said bushing-sections to 45 the inner sides of said jaws, and means projecting from the exposed forward end of said chuck for operating said catches. It also consists in the more specific construction and combination of parts, as shown in the drawings and hereinafter described, and defined 50 by the claims.

In the drawings, Figure 1 is a side elevation, partly in section, of a chuck embodying my invention. Fig. 2 is a transverse sectional view through the chuck-core on line 55 22 of Fig. 1, and Fig. 3 is a view showing the outer surface of one of the bushing-sections.

Referring to the parts by letters, A represents the tubular spindle of a lathe, which spindle is to be rotatably mounted in suitable bearings.

C represents the shell of the chuck, which is secured to the front end of said spindle, preferably by being screwed onto said front end, substantially as shown. This shell is 65 of the usual form—that is to say, it internally has the form of the frustum of a cone.

The tubular core B of the chuck, as shown, is of the usual form and construction. Its front end has externally the form of the 70 frustum of a cone, and it is longitudinally slitted from the front end, whereby to form the jaws b, which are forced inward against the work-rod as said core is moved forward in the shell. In the particulars already mentioned the chuck is not new, but is, on the contrary, of well-known form. It has not therefore been thought necessary to show or describe any mechanism for moving said core forward to cause the contraction of its jaws. 75 80

D D represent bushing-sections which are removably secured to the inner faces of the jaws b of the core B. The thickness of these bushing-sections will be determined by the size of the work-rod with which they are to 85 be used, and the form of their inner surfaces will be such as to adapt them to grasp such work-rod, whether it be cylindrical, square, or any other shape. If the chuck is not at any time capable of grasping and holding any 90 particular work-rod upon which one wishes the machine to operate, the bushing-sections are removed and others of proper thickness and internal configuration are substituted.

There must be a driving connection between the jaws b and bushing-sections D, whereby they are compelled to rotate in unison, and relative endwise movement of said core and bushing-sections must likewise be prevented. The specific construction for effecting the results mentioned is as follows: On the inner face of each jaw, at the forward 95 100

end thereof, is a flange b' , which enters a rabbit d in the front edge of the corresponding bushing-section. Two lugs $b^2 b^2$ on the inner face of each jaw engage with the rear edge 5 of the bushing-section. The described construction prevents relative endwise movement of the bushing-sections and jaws. These lugs $b^2 b^2$ also engage with the sides of a tail d' on said bushing-section. Preferably 10 the proximate faces of these lugs are undercut and the side edges of said tail are beveled to fit. The engagement of the tails d' between the lugs $b^2 b^2$ furnishes the necessary driving connection between the jaws and 15 bushing-sections. The described operative connection between the said bushing-sections and jaws will be maintained just so long as the bushing-sections are held in the described position relative to said jaws and are prevented 20 from falling inward toward the axis of the spindle. This last-named result is secured, as shown in the drawings, by means of spring-catches E , carried by the jaws, which catches engage with lips d^3 on the outer 25 faces of said bushing-sections. These spring-catches are hooks projecting inward from blocks e , each of which is movable longitudinally in a hole b^5 through one of the jaws. A rod c' , which is movable endwise in a longitudinal recess b^6 in said jaw, passes through 30 the block and is fastened to it by a set-screw e^2 . The end of this rod extends out of the exposed forward end of the core, and therefore these devices, which hold the bushings 35 in operative relationship to the jaws, may be operated from the front end of the chuck without separating its core and shell. A spring e^3 in the end of the hole b^6 acts to move 40 said rod and catch forward, whereby the latter engages with the lip on the bushing-section. A longitudinal groove d is formed in the rear side of each bushing-section, and the groove slides over the inner end of the catch when a bushing-section is being removed or 45 replaced.

Having described my invention, I claim—

1. In a chuck for lathes, &c., the combination with a core having a plurality of compressible jaws, and bushing-sections adapted 50 to be held against the inner faces of said jaws, of catches for so holding them, and mechanism projecting from the forward end of said core for operating said catches, substantially as and for the purpose specified.
2. In a chuck for lathes, &c., the combination with the longitudinally-split core thereof having the flange b' and lugs $b^2 b^2$ on the inner surface of each jaw, of the bushing-sections 55

each having a tail on its rear end, and means for holding said bushing-sections 60 against said jaws and in engagement with said flange and lugs, substantially as and for the purpose specified.

3. In a chuck for lathes, &c., the combination with the tubular spindle, the chuck-shell 65 secured to its front end, and the tubular chuck-core which is longitudinally split to form a plurality of compressible jaws, of bushing-sections, catches for removably holding said bushing-sections severally on the inner sides 70 of said jaws, and means, which project from the exposed front end of the core, for operating said catches, substantially as and for the purpose specified.

4. In a chuck for lathes, &c., the combination with the chuck-core which is longitudinally split to form a plurality of compressible jaws, said jaws having shoulders on their inner faces, of bushing-sections adapted to lie 75 against the inner faces of said jaws between 80 said shoulders, and spring-catches carried by said jaws and adapted to engage with said bushing-sections to hold them against said jaws, substantially as and for the purpose specified.

5. In a chuck for lathes, &c., the combination with the chuck-core which is longitudinally split to form a plurality of compressible jaws, which jaws have the inwardly-projecting flange b' and the lugs $b^2 b^2$ whose proximate 90 faces are undercut, and spring-catches carried severally by said jaws and projecting inward therefrom, of bushing-sections, each having a tail on its inner end and the lip and the longitudinal groove on the outer face, substantially as and for the purpose specified.

6. In a chuck for lathes, &c., the combination with the chuck-core which is longitudinally split to form a plurality of compressible jaws, each of said jaws having a lateral hole 100 through it and a longitudinal recess crossing said hole, a block in said hole and having a hook on its inner face projecting through said jaws, a rod in said recess passing through and attached to said block, and a spring in the 105 bottom of said recess, of bushing-sections lying against the inner faces of said jaws, each having a lip on its outer face for engagement with one of said hooks, substantially as and for the purpose specified.

In testimony whereof I hereunto affix my signature in the presence of two witnesses.

AMBROSE SWASEY.
